United States Patent Office

Des. 179,601
Patented Jan. 29, 1957

179,601

SLIDE CONTAINER

Rex B. Husted, Rochester, N. Y., assignor to Eastman Kodak Company, Rochester, N. Y., a corporation of New Jersey

Application February 6, 1956, Serial No. 40,039

Term of patent 14 years

(Cl. D61—1)

FIG. 1

FIG. 2

FIG. 3

FIG. 4

FIG. 5

Fig. 1 is a top plan view of a slide container, showing my new design;

Fig. 2 is a side elevational view thereof;

Fig. 3 is a bottom plan view thereof;

Fig. 4 is an end elevational view thereof; and

Fig. 5 is an end elevational view taken from the opposite end from that shown in Fig. 4.

I claim:

The ornamental design for a slide container, as shown.
